Primary Examiner — Melanie H Tung*(74) Attorney, Agent, or Firm* — Harness, Dickey & Pierce(57) **CLAIM**

I claim the ornamental design for an electronic device display with an animated graphical user interface, as shown and described.

DESCRIPTION

FIG. 1 is a front view of the first image of an electronic device display with an animated graphical user interface showing my new design;

FIG. 2 is a front view of a second image thereof;

FIG. 3 is a front view of a third image thereof;

FIG. 4 is a front view of a fourth image thereof; and,

FIG. 5 is a front view of a fifth image thereof.

The broken line showing the electronic device display in all views forms no part of the claimed design.

The appearance of the image transitions sequentially between the images shown in FIGS. 1-5. The process or period in which an image transitions to another forms no part of the claimed design.
